CLAIM

The ornamental design for a gripper for wafer cassette, as shown and described.

DESCRIPTION

FIG. 1 is a front view of a gripper for wafer cassette showing our new design;

FIG. 2 is a rear view thereof;

FIG. 3 is a right side view thereof;

FIG. 4 is a left side view thereof;

FIG. 5 is a top view thereof;

FIG. 6 is a bottom view thereof;

FIG. 7 is a front, top, right side perspective view thereof;

FIG. 8 is a rear, bottom, left side perspective view thereof; and

FIG. 9 is another perspective view thereof, shown in a used condition attached to a device in broken lines; and,

FIG. 10 is another perspective view thereof, shown in a used condition attached to a device in broken lines.

Shaded areas in the figures define the claimed portions of the design.

The broken lines shown in the figures depict portions of the gripper for wafer cassette that form no part of the claimed design.
